Primary Examiner — Melanie H Tung*(74) Attorney, Agent, or Firm* — Leanna Taveggia Farrell; David D. Brush; Westman, Champlin & Koehler, P.A.(57) **CLAIM**

The ornamental design for a portable electronic device with graphical user interface, as shown and described.

DESCRIPTION

FIG. 1 is a front view of a first embodiment of the portable electronic device with graphical user interface; and, FIG. 2 is a front view of a second embodiment of the portable electronic device with graphical user interface. The broken lines shown in the drawings of a portable electronic device and certain graphic features of the graphical user interface form no part of the claimed design.
